Application December 2, 1932, Serial No. 645,456

8 Claims. (Cl. 232—41)

This invention has to do with a construction of a receptacle or compartment especially adapted to receive articles and to retain such articles secure from unauthorized access pending collection thereof.

The invention has especially to do with a receptacle intended for domestic use, wherein household deliveries may be made and rendered secure against tampering until the articles placed in the receptacle are collected.

It is well known that many times articles delivered by tradesmen for household use are frequently left in places exposed to weather or theft, especially in the event that the deliveries are made in the mornings, or at such times when there is no one available to receive them; and frequently the receiving of such articles occasions a substantial amount of inconvenience to the household.

It will be apparent that, while the improved device is especially designed for the purpose of receiving such articles and for rendering them secure, until conveniently collected, against access by unauthorized individuals, the improved receptacle is adapted, obviously, for a wide range of use, as will be determined by the individual case, or purpose for which the receptacle, or compartment, is desired to be employed.

Although the device is of general adaptation, it is especially intended that it be installed on the outside of a door or other wall support and operated from the inside of the door without requiring the door to be opened until such time as it is convenient to remove the articles placed therein. This materially reduces the amount of exposure, especially in cold or inclement weather, to which a household occupant is subjected in receiving these articles when delivered.

To this end, the invention contemplates the inclusion of improved locking instrumentalities which are releasable by mechanism operable from the inside of the room through devices extending through the door or wall support and into the receptacle.

These locking instrumentalities include devices which, upon release, automatically open the cover of the receptacle, so that the deliveries may be placed therein, and then snap into locking position when the cover is closed by the individual making the delivery, so that, except for the operating devices, the locking instrumentalities are entirely inaccessible when the cover of the box has been shut.

With such adaptation for general use in mind, for the principal purpose for which the recep-

tacle or box is designed, it may be noted that the receptacle includes a box adapted to be secured to the outside of a door, or similar locations convenient for the depositing therein of domestic delivery articles. This box is provided with a hinged lid or closure member, having novel locking instrumentalities which will be hereinafter described in detail, which instrumentalities are automatically operable incident to the closing of the lid to lock the lid against any opening thereof until the locking instrumentalities are released by actuation of actuating devices positioned interiorly of the door, and thereby rendered available only to an individual accessible to the actuating devices. Upon suitable operation of these devices, the locking instrumentalities may be readily released for the convenient collection or removal of articles deposited within the box, which meanwhile have been secured against molestation by unauthorized individuals or prowling animals. The improved mechanism includes instrumentalities whereby, immediately upon release of the locking devices, the cover will automatically open.

The invention may take many different forms embracing the same general principles, several of which forms are illustrated in the accompanying drawings, and the details of which will be fully set forth hereinafter.

In the drawings:

Figure 1 is a vertical sectional view of a compartment, box, or receptacle embracing certain novel features included in this invention.

Figure 2 is a side view.

Figure 3 is a top view.

Figure 4 is a detailed fragmentary sectional view through the top part of the receptacle, showing the construction and actuation of the locking devices for the box lid.

Figure 5 is a similar view, but showing the automatic opening responsive to release of the locking instrumentalities.

Figure 6 is a view showing the lid in open position.

Figure 7 is a view similar to Figure 4, but showing a different form of locking instrumentalities from those illustrated in the preceding views.

Figure 8 is a fragmentary view showing one form of spring member adapted for opening the box lid upon unlocking thereof.

Figure 9 is a fragmentary sectional view similar to Figure 4, but showing a modified form of lid releasing device suitable for use when the box is divided into a plurality of compartments.

Figure 10 is a vertical sectional view taken on the line 10—10 of Figure 11.

Figure 11 is a top view of a box arranged into a plurality of separate compartments, each of which is desirably provided with an independently operable cover, the view showing common releasing instrumentalities for the covers.

Figure 12 is a perspective view of another form of spring for actuating the box lid, which also serves as a locking for the lid.

Figure 13 is a plan view of a washer employed for retaining the releasing instrumentalities in position.

Figure 14 is a sectional view through the washer of Figure 13, taken on the line 14—14 of Figure 13.

Figure 15 is a fragmentary section showing the mounting of a locking pin or lug employed for locking the cover in place when closed, and

Figure 16 is a view thereof, looking in the direction of the arrows of line 16—16 of Figure 15.

Figure 17 is a detail view of the lid releasing device, showing the means provided for adjusting the length thereof in accordance with the thickness of the door or other mounting of the box.

Figure 18 is a sectional view through the device of Figure 17, taken on the line 18—18 of Figure 17, looking in the direction of the arrows.

Figure 19 is a sectional view on the line 19—19 of Figure 17, looking in the direction of the arrows.

In the drawings, referring first to the form of invention illustrated in Figures 1 to 6 inclusive, it will be seen that the invention embraces a compartment, receptacle, or box, 1 having a cover or lid 2 connected to the box 1 by means of a hinge 3.

The box 1 is shown as being mounted in position upon a wall support such as a door, or equivalent mounting 4, by means of suitable securing devices 5, which may be screws or bolts passed into the mounting 4 through suitable holes in the walls of the box. It will be understood that this box is located where articles may be conveniently placed therein, so that upon closing and locking of the lid, the articles are rendered inaccessible against theft or molestation.

For this purpose on the inside of the box, at a convenient point therein, is suitably secured a locking lug or pin 6 adapted to engage with an opening 7 in a leaf spring 8 riveted or otherwise secured as at 9 to the bottom of the lid 2.

The shape of the spring is one of the principal features of this invention, since it enables an automatic lifting of the lid when the spring is released from the locking lug, or catch 6. This feature will be described in more detail hereinafter, when considered with reference to the instrumentalities employed for releasing the spring from locking engagement with the catch.

The releasing instrumentalities are mounted in the door 4, in such a manner as to be accessible from the side of the door opposite to that upon which the box 1 is secured. Into a suitable recess 10 cut into this door there are positioned the aforesaid releasing instrumentalities which include a plunger rod 11 having a rounded end 12 extending interiorly of the box 1 through an opening 13 in the walls of the box so that the end 12 of this rod will be positioned adjacent the inward bent portion 14 of the spring 8. It will be noted that the spring 8 is generally of an inwardly bent configuration, but that the portion 14 is further bent so as to ride in an upward direction against

the rounded end 12 of the rod 11 when the rod is pushed against the spring.

The rod 11 is provided with an enlarged head 15 forming a collar against which acts the springs 16 so that the projection 17 of the head 15 forms a collar against which acts the 11 retracted out of engagement with the spring 8 in a manner which will be obvious from the drawings. The parts 11, 15, and 17 may be integral, and the resulting releasing device or 10 plunger is secured in its mounting by means of a washer 18 having a hole 19 therethrough, through which hole is passed the extension 17. It will be obvious that when this device is assembled, the parts 11, 15, 16, and 17 are suitably 15 positioned within the recess 10 with the end 12 of the rod projecting within the interior of the box 1. The washer 18 is then secured in position around the extension 17 by means of screws or other fastening devices 19a inserted through 20 holes 20 in the washer.

It will be seen, therefore, that when the lid 2 is closed, the spring 8 will engage the catch 6 because of the inherent resiliency of the spring, and as soon as the opening 7 in the spring registers with the catch 6, the spring 8 snaps into locking engagement with the catch and holds the lid 2 securely locked, thereby preventing access to the interior of the box until the spring is released.

As has been indicated previously, this release is effected by pressing upon the extension or button 17 so that the releasing device is moved inwardly against the pressure of the spring 16 sufficiently to engage the end 12 of the rod 35 against the portion 14 of the spring. This action presses the spring inwardly out of engagement with the catch 6, and because of the configuration of the part 14 of the spring, it will cam upwardly along the end of the rod, thus 40 automatically releasing the lid and causing the lid to fly open. The box is then accessible for the reception of whatever articles are to be placed therein.

When these articles have been placed into the 45 box, the lid 2 is closed, and the portion 14 of the spring will serve to properly guide the spring in its movement against the catch 6 until the opening 7 snaps over this catch, thereby again locking the box; and since the releasing device is 50 inaccessible to a prowler, the articles deposited in the box will be maintained secured safe from disturbance until such time as they may be conveniently removed.

In the modification shown in Figure 7, there is 55 illustrated a somewhat different type of locking mechanism, the principle of operation of which however is similar to that already previously described. In this modification there is employed a bracket 21 secured by rivets 22 to 60 the underside of the cover 2. In this bracket there is slidably positioned a latch 23, held normally in extended position by the spring 24 positioned at the rear of the latch 23. The latch 23 is thereby held in locking engagement with a 65 catch 25 mounted on the wall of the box 1, there being positioned intermediate this catch 25 and the cover 2 a leaf spring 26 tending to act against the cover to force it open as soon as the latch 23 is withdrawn from engagement with the catch 25. The spring 26 is secured to the bracket 25 by a screw or equivalent fastening members 27.

To effect withdrawal of the latch 23 in order to release the cover, the latch is provided with 75

an extension 28 which is adapted to be engaged by the rod 11 when the latter is positioned inwardly as described above. As soon as the latch 23 is released, the spring 26 opens the cover 2 so that the articles may be deposited in the box. Upon closing the cover, the latch 23, being maintained in extended position through action of spring 24, will engage the catch 25, but because of the curved end of the latch 23, continued 10 closing movement of the cover will press the latch backwardly against pressure of spring 24 until the latch has passed the catch 25, when the spring 24 snaps it into locking position, thus securing the cover.

If desired, the box 1 may be sub-divided into a plurality of compartments, as indicated at 29, see Figure 11, each of which compartments is provided with its own cover, which covers may be independent of each other, so that certain 15 20 25 of the covers may be locked in position for securing articles placed in the corresponding compartments, while the remaining covers are still released for enabling the remaining compartments to be maintained accessible for receiving additional articles to be placed into the box.

In this form of the invention, each cover may be provided with either form of locking devices previously described, there being illustrated the use of a spring and catch of the type illustrated 30 in Figures 1 to 5 inclusive. It is desirable, however, to release these covers simultaneously, and for this purpose, the rod 11 may carry a bar 30 extending through the compartment walls by virtue of slots 31 provided therein, which slots 35 guide the rod 30 in its movement. It is believed that the operation of this form of the invention will be obvious from the foregoing.

It is obvious that the doors or other mountings for the box are not of standard thickness, so that, 40 unless means be provided for enabling the releasing instrumentalities previously described to be shortened where the thickness of the mounting may require it, as otherwise the rod 11 might be too long for suitable release of the locking devices. Such means are indicated in Figure 17, 45 wherein the rod 11 is shown as provided with, along its length, sections 32 cut, as indicated at 33, so that the sections 32 may be broken off as required from the remainder of the rod. The 50 length of this rod may therefore be made to compensate for the thickness of the mounting upon which the box is secured.

It will be observed that in all cases the releasing instrumentalities extending through the wall support form a plunger which is controlled 55 remotely from the receptacle for releasing the otherwise inaccessible latch within the receptacle. It will be also seen that the curved end 60 portions of the spring latch fingers provide a camming surface which has a component of incline intersecting the lines of travel of the cover plate during pivotal movement, whereby pressure exerted laterally against the spring finger at the camming surface, see part 14 of the spring 65 finger 8 for example, will stress the spring finger both laterally and longitudinally upon engagement of the plunger rod 11 therewith so as to release the engagement of the spring finger with the cooperating catch 6, the longitudinal 70 stressing of the spring finger causing the cover plate 2, Figure 2, to spring pivotally away from the latching position of the spring finger. Obviously, the interior latch mechanism is, in each 75 form of the invention, accessible when the lid is

closed only through operation of the plunger extending through the wall support.

It may be noted in connection with the modification shown in Figure 7, that the bracket 21 is provided with a slot 28a through which extends the projection 28, which is screwed into the latch member 23. The slot 28a thus limits the movement of the latch and retains the latch properly in position within the bracket 21.

If desired, the receptacles may be suitably insulated against heat and cold in any desired manner as by the provision of an asbestos lining, not shown.

Having thus described our invention, what we claim as new and desire to secure by Letters Patent of the United States, is—

1. A receptacle of the character described, adapted to be mounted upon one side of a door or equivalent mounting means, the said receptacle having a cover, a hinge interconnecting the cover and receptacle, locking means disposed interiorly of the receptacle for securing the cover in locked position to render inaccessible articles placed within the receptacle and instrumentalities for releasing the locking means and extending through the said mounting means and interiorly of the receptacle, the instrumentalities being accessible for operation only from the side of the door or equivalent mounting means opposite to the side upon which the receptacle is mounted, the said locking means including devices engageable with the releasing instrumentalities and having a portion shaped to cooperate with the instrumentalities for automatically opening the cover of the receptacle incident to release of the locking means.

2. A receptacle of the character described adapted to be mounted upon one side of a door or equivalent mounting means, the said receptacle having a cover, a hinge interconnecting the cover and receptacle, locking means disposed interiorly of the receptacle for securing the cover in locked position to render inaccessible articles placed within the receptacle, and instrumentalities mounted within the door or equivalent mounting means and accessible from the side thereof opposite to that upon which the receptacle is mounted, for releasing the locking means, the said locking means including devices for automatically opening the cover of the receptacle incident to release of the locking means.

3. A receptacle of the character described adapted to be mounted upon a wall support, the said receptacle having a cover pivoted to the receptacle, a spring latch finger fixed to the cover and extending therefrom in the direction of lines of travel of the cover during its pivotal movement and transversely of the axis of the pivot, a cooperating catch member for engagement with the spring finger when the cover is in closed position, and a plunger extending through the wall support and into the receptacle for engaging with the spring latch finger and controlled remotely from the receptacle for releasing the spring finger from the catch, the spring finger being curved to provide a camming surface having a component of incline intersecting the lines of travel of the cover during pivotal movement thereof, whereby pressure exerted laterally against the spring finger at the camming surface will stress the spring finger both laterally and longitudinally, the former to release the engagement of the spring finger with the cooperating catch and the latter to spring the cover plate piv-

totally away from the latching position of the spring finger.

4. A receptacle of the character described adapted to be mounted upon a wall support, the 5 said receptacle having a cover, a hinge interconnecting the cover and receptacle, a lug on the receptacle, a latch on the cover for interlocking with said lug, and a plunger extending through the wall support for releasing the otherwise inaccessible latch from the lug, the latch including a spring finger engageable by the plunger and actuatable thereby to open the cover incident to release of the latch.

5. A receptacle of the character described 15 adapted to be mounted upon a wall support, the said receptacle having a cover, a hinge interconnecting the cover and receptacle, a lug on the receptacle, a latch on the said cover for interlocking with the said lug and a plunger extending through the wall support for releasing the otherwise inaccessible latch, the latch including a cammed spring finger actuatable by the plunger for opening the cover incident to release of the latch.

20 6. In delivery receiving boxes, the combination with a container, of a cover plate therefor pivoted to the container, a spring latch finger fixed to the cover and extending therefrom in the direction of lines of travel of the cover during its pivotal movement and transversely of the 25 axis of the pivot, a cooperating catch for engagement with the spring finger to lock the same against movement when the cover is in its position closing the container, the spring finger being curved to provide a camming surface having a component of incline intersecting the lines of 30 travel of the cover during pivotal movement,

whereby pressure exerted laterally against the spring finger at the camming surface will stress the spring finger both laterally and longitudinally, the former to release the engagement of the spring finger with the cooperating catch and the latter to spring the cover plate pivotally away from the latching position of the spring finger.

5 7. Locking mechanism for compartments and the like, comprising in combination, a closure member for the compartment, cooperating latching instrumentalities disposed interiorly of the compartment and closure member, the instrumentalities including a spring latching finger, and instrumentalities for stressing the said spring finger both laterally and longitudinally to release the engagement of the spring with its cooperating latching instrumentalities and to spring the said closure member away from its closed position.

10 8. In a device of the character described, a 20 receptacle having a hinged cover adapted to be mounted upon a supporting surface, locking means for securing said cover in closed position, said locking means comprising a catch secured to the inside of said receptacle and closely adjacent the zone of the cover, a resilient member mounted on the cover and movable therewith for engaging said catch to retain the cover locked when in closed position, said resilient member having a part extending below said catch, and 25 means for operating said member to release the lock, which comprises a reciprocable plunger adapted to engage said part to thereby move said member out of engagement with the catch.
